UNITED STATES PATENT OFFICE

FRÉDÉRIC PIRLOT, OF IXELLES, BELGIUM

VIBRATING SIFTING SCREEN

Application filed July 26, 1930, Serial No. 470,981, and in Belgium August 3, 1929.

In sorting apparatus having a vibrating sieve in particular, the vibrating sieve may be actuated by a device provided with one or more rotary discs with an unbalanced weight 5 capable of being moved under the action of centrifugal force.

In these apparatuses the shafts of the rotary discs are prevented from moving transversely to the alternating movement to be 10 produced by means of guides against which they bear along a length equal to the amplitude of the alternating movement obtained. It thus results that the work of friction is 15 relatively high.

For the purpose of reducing this frictional work the invention contemplates supporting the said discs by a pivoted lever. The reduction of the frictional work is the greater 20 the smaller the angular movement of the lever, and consequently the further the pivotal point of the lever is removed from the parts supporting the discs.

In apparatus of the known type referred 25 to it is also known to vary the amplitude of the alternating movement by radially moving the unbalanced weight. The devices of this character are generally provided with two eccentrics located one within the other and of 30 which the angular position may be varied suddenly. It thus results that the amplitude of the alternating movement varies suddenly in passing from one position to the other of the eccentrics. It is, however, not always 35 possible to obtain the sorting exactly desired.

To remedy this inconvenience, the present 40 invention contemplates the possibility of moving the unbalanced weight progressively. This movement may be effected with great facility by traversing a nut secured to the movable weight by a screw threaded rod locked radially, but which can be rotated about itself.

The invention also relates to a particular 45 device for actuating the vibrating sieve of a sorting apparatus with a vibrating sieve.

According to the invention this device is provided with one or more rotary discs with 50 an unbalanced weight capable of being moved under the action of centrifugal force

in the direction of alternating movement to be produced.

It is known to use such devices for actuating vibrating frames. In this case, as the 55 whole sieve moves as a unit at the same time as the frame, a vibration proper of the sieve is not obtained, and this is rapidly obstructed when the meshes are small. It is also known to cause the sieve to vibrate whilst the frame 60 remains stationary. These vibrations are particularly obtained by means of electromagnets which attract the sieve in one direction, then allow it to return to its first position by reason of its tension. In this case, the sieve 65 moves less rapidly than in the case of the vibrating frame. With the actuating device according to the invention the sieve is never 70 obstructed as its vibration is controlled in a sudden manner in both directions.

If in a sorting apparatus with a vibrating 75 sieve there are used two superposed sieves it is of advantage, in order to obtain good results, that the two sieves make between them a certain angle, generally of some degrees.

For the purpose of rendering uniform the 80 manufacture of the frames provided with sieves, the invention contemplates for each frame disposing the sieve in a plane forming with the middle plane of the frame an angle equal to half the said angle.

In this manner, for inclining the sieves 85 suitably relatively to one another, it suffices to place on a definite frame an identical frame which, however, has been turned through 180° about an axis situated in its middle plane and forming with the plane of the sieve an angle equal to half the angle which the sieves should include between them.

The invention also includes a device for 90 adjusting the tension of a sieve. It is known to effect this adjustment by moving the clamps situated along one of the edges disposed transversely to the direction of the tension. These clamps were moved independently of one another in such a manner 95 that it was very difficult to tension the sieve uniformly.

In order to remedy this defect, the invention 100 contemplates moving simultaneously

through the same amount the said clamps by means of a single mechanism either during operation or whilst stationary.

In order to avoid when modifying the tension of a sieve, that the movement of this produces a certain wedging of the hinges of a rod by which the sieve receives its alternating movement the invention also provides that these hinges are such that the rod can 10 pivot freely during the tension of the sieve.

The invention finally relates to a device for securing a vibrating sieve for a sorting apparatus.

In such an apparatus there are more finer 15 materials on the portion of the sieve situated underneath the point of discharge than on the portion at the opposite end.

In order to cause this large quantity of fine 20 materials to disappear rapidly the invention contemplates causing the said portion loaded with the fine materials to be oscillated more energetically than the other portions. For this purpose, the edge of the sieve along this portion is secured to the frame by hinges 25 facilitating the vibrations of the sieve.

Other details and features of the invention 30 will appear in the course of the description of the drawing accompanying the present specification and which illustrate in perspective, by way of example and not in a limiting sense, a form of construction of the invention.

Figure 1 is a view, partly broken away, of 35 a sorting apparatus with vibrating sieves according to the invention.

Figure 2 is a view to a larger scale of the device adapted to actuate the sieves.

Figure 3 also illustrates to a larger scale 40 means for actuating and securing one of the clamps serving to hold the sieve.

Figure 1 shows a sorting apparatus provided with superposed sieves 2 each mounted in a frame 3. These sieves must vibrate by reason of their connection by means of 45 oscillating rods 4 to a disc 5 rotated, for example, by a belt 6, the said disc having an unbalanced weight. The action of centrifugal force on this weight tends to move the disc in the direction in which this centrifugal force has at each instant.

This movement is only permitted in a direction substantially normal to the sieve by mounting the disc 5 on a pivoted lever 7 of which the length is relatively large in such 55 a manner that the path described by the centre of the disc 5 may almost be considered as rectilinear and of which the midposition is substantially parallel to the plane of the sieve. The lever 7 is mounted upon the 60 frame 3 by the pivot 7a.

In order to vary the amplitude of the movements of the disc 5 it is particularly possible to vary the distance between the centre of gravity of the unbalanced weighted disc from 65 the axis of rotation. This variation of the

distance may be effected for example by radially moving a mass 5a carried by the disc 5 (Figure 2).

According to the invention the mass 5a is located in a recess 5b of the disc 5 and serves as a nut for a screw threaded rod 5d prevented from moving radially, but which can be turned about itself. It is thus possible to easily effect a progressive movement of the mass 5a forming the weight of the disc 5.

When a sorting apparatus with vibrating sieve is provided, as in the case illustrated in Figure 1, with a number of superposed sieves it is of advantage for the sieves to be arranged relatively to one another at a certain angle, generally a few degrees.

In order to render uniform the manufacture of frames provided with sieves, the invention contemplates disposing each sieve 2 in a corresponding frame 3 in such a manner that the middle plane of the sieve is set relatively to the middle plane of the frame at an angle equal to half the said angle. In this manner a suitable angle between the two sieves may be obtained by superposing two identical frames of which one has been turned through 180° relatively to the other about an axis situated in its middle plane and forming with the plane of the sieve an angle equal to half the angle which the sieves should have relatively to one another.

For the purpose, of effecting rapidly a uniform adjustment of the tension of all the wires of the sieve, the invention contemplates effecting simultaneously the movement of the clamps by which this adjustment is generally effected. For this purpose (Figures 1 and 3) the clamps 8 which have a screw threaded portion 8a are provided with a nut 9 of which the periphery 9a is toothed and gears with a worm 10 which may be rotated for example by operating a hand wheel 10a. It will be understood that a worm 10 is provided for each sieve. These worms pass through suitable 110 bearings mounted on the frame.

Near one end of the frame is provided a hopper 11, by which the materials to be sorted are discharged on the sieve. In some cases, it may be desirable to permit of freedom of movement of the sieve at this end. For this purpose each rod 8 passes through a large hole in the frame 3 and through a member 12a having a hole for the passage of the rod 8, this hole being of the same diameter as the diameter of this rod. The rod 8 also passes through a hole in a member 12b, this hole being elongated so as to enable the rod 8 to move up and down in accordance with the movements of the sieve. In order to enable the movement of the rod 8 to take place freely the members 12a and 12b are provided with interengaging correspondingly shaped spherical surfaces.

On the end of the sieve opposite to that

upon which the hopper 11 is situated, the sieve is clamped by ordinary fixed clamps not shown.

Finally the invention also contemplates that the rods 4 connecting the sieves together as also the upper sieve to the mechanism imparting the alternating movement thereto are formed in such a manner that the adjustment of the tension of the sieve does not produce a wedging of the hinges. In Fig. 2 there is shown in detail the rod 4 which connects the upper sieve 2 to the lever 7. Tension is effected by moving the clamps 8 of Fig. 1 in the direction of the arrow X so as to stretch the sieve.

The pivot 4a which connects the rod 4 to the lever 7 is positioned perpendicularly to the direction X in which direction tension takes place. A bar such as 13 distributes throughout the length of the sieve the action transmitted by the rod 4.

It will be understood that the invention is not solely limited to the form of construction illustrated and that modifications may be made in the shape, the arrangement and constitution of the elements partaking in its construction without departing from the scope of the present invention.

What I claim is:

- 30 1. A sifting apparatus comprising a fixed frame, sieves therein, a rotatable unbalanced weight, a pivoted lever for supporting the axis of said rotatable unbalanced weight, means for rotating the latter and rods between the pivoted lever and the sieves disposed substantially perpendicular to the latter for transmitting directly to the latter the vibration of the pivoted lever in a direction perpendicular to the plane of these sieves.
- 40 2. A sifting apparatus comprising a fixed frame, a sieve therein, a rotatable unbalanced weight, a pivoted lever for supporting the axis of rotation of said rotatable unbalanced weight, means for rotating the latter, a rod between the pivoted lever and the sieve disposed substantially perpendicular to the latter for transmitting directly to the latter the vibrations of the pivoted lever in a direction perpendicular to the plane of this sieve, means for varying the tension of the sieve and pivots for connecting the said rod to the pivoted lever and to the sieve, the axes of said pivots being directed transversely to the direction of tension of the sieves.
- 50 3. A sifting apparatus comprising a fixed frame, sieves therein, a rotatable unbalanced weight, a pivoted lever for supporting the axis of rotation of said rotatable unbalanced weight, means for rotating the latter, a rod between the pivoted lever and the adjacent sieve disposed substantially perpendicular to this sieve for transmitting directly to the latter the vibrations of the pivoted lever in a direction perpendicular to the plane of this sieve, rods between the successive sieves,

means for independently varying the tension of the sieves, and pivots for connecting the said rods to the pivoted lever and to the sieves, the axes of said pivots being directed transversely to the direction of tension of the sieves.

In testimony whereof I affix my signature.
